(57) **CLAIM**

The ornamental design for a reel seat for use on fishing rod, as shown and described.

DESCRIPTION

FIG. 1 is a perspective view of a reel seat for use on fishing rod embodying my new design;

FIG. 2 is a front view thereof;

FIG. 3 is a top plan view thereof;

FIG. 4 is a bottom view thereof;

FIG. 5 is a left side view thereof;

FIG. 6 is a right side view thereof;

FIG. 7 is a sectional view along 7—7 thereof; and,

FIG. 8 is a referential view showing use state thereof.

The broken line showing of environment in the drawings is included for the purpose of illustrating only and forms no part of the claimed design.
